UNITED STATES PATENT OFFICE.

CHARLES W. BAKER, OF WAVERLY, MICHIGAN.

HAY-BINDER.

SPECIFICATION forming part of Letters Patent No. 379,555, dated March 20, 1888.

Application filed July 19, 1887. Serial No. 244,727. (No model.)

To all whom it may concern:

Be it known that I, CHARLES W. BAKER, a citizen of the United States, residing at Waverly, (Paw Paw P. O.,) county of Van Buren,

5 State of Michigan, have invented a new and useful Hay-Binder, of which the following is a specification.

This invention has for its object the apparatus substantially as below described and 10 claimed, in combination with a hay-rack for binding a load of hay and the like.

In the drawings forming a part of this specification, Figure 1 is a rear elevation; Fig. 2, a plan; Fig. 3, a lettered detail enlarged; and 15 Fig. 4 shows broken details enlarged from Fig. 1.

Referring to the letters of reference marked on the drawings, B is the body of the rack, and c c are the obliquely-angled sides of the 20 rack. Fixed at suitable locations on the rack are loops or eyes e, preferably a series of them on each side at the ends, and, if desired, at the center on each side. The end ropes, a, are attached to these eyes, Figs. 1 and 4. The ropes 25 a have a metal eye in the end, as at v, by which means the ropes are lengthened and shortened in accordance with the size of the load A. The ends of these ropes are attached to any desired eye e, in accordance with the 30 width of the load. As here shown, a rope a

is employed at each end of the load; but they may be used at the sides, either conjointly with like ropes at the ends or at each of the four corners, as desired.

Centrally attached to the ropes a are pulleys u D'. D is a binding rope folded around these pulleys, one end being attached to pulley u and the other end tied around the flanged head r of the pulley D'. By drawing on this rope D the ropes a are drawn tight against the 35 ends of the load, or against the sides and corners, as the case may be, and the rope D forms a top binder to the load. Such an apparatus 40 will be found useful in hauling hay over rough land, and to market as well. 45

Having thus described my invention, what I claim is—

The rack having the eyes, the ropes provided with the eyes at the ends, the pulleys, one having a flanged head and the binding-rope attached to one pulley at one end and the other end detachably fastened to the said flanged head, substantially as set forth. 50

In testimony of the foregoing I have hereunto subscribed my name in presence of two 55 witnesses.

CHARLES W. BAKER.
